US00D629891S

(12) **United States Design Patent**
Virr et al.

(10) **Patent No.:** **US D629,891 S**
(45) **Date of Patent:** **** Dec. 28, 2010**

(54) **CUFF FOR AIR DELIVERY TUBE**

(75) Inventors: **Alexander Virr**, Balmain (AU); **Nathan John Row**, Coogee (AU); **Mark Bertinetti**, Ermington (AU); **Andrew Roderick Bath**, Quakers Hills (AU)

(73) Assignee: **ResMed Limited**, Bella Vista (AU)

(**) Term: **14 Years**

(21) Appl. No.: **29/311,183**

(22) Filed: **Jan. 12, 2009**

(51) **LOC (9) Cl.** **24-02**

(52) **U.S. Cl.** **D24/129**

(58) **Field of Classification Search** **D24/107, D24/110, 110.4, 110.5, 110.6, 127, 128, 129, D24/164; 128/200.24, 201.22, 202.27, 203.27, 128/204.18, 205.25, 206.15, 206.21; 138/121, 138/122; 156/143; 285/260; 604/27**

See application file for complete search history.

(57) **CLAIM**

The ornamental design for a cuff for air delivery tube, as shown and described.

DESCRIPTION

FIG. 1 is a front perspective view of a cuff for air delivery tube according to our design;

FIG. 2 is a front view thereof, with the rear view being a mirror image thereof;

FIG. 3 is a top view thereof, with the bottom view being a mirror image thereof;

FIG. 4 is a right side view thereof;

FIG. 5 is a left side view thereof;

FIG. 6 is an alternate perspective view, from the front and right side; and,

FIG. 7 is an alternate perspective view, from the front and left side.

The broken lines represent environmental structure of the cuff for air delivery tube and do not form a part of the claimed design.

1 Claim, 6 Drawing Sheets
